[57] CLAIM

The ornamental design for a vinyl sheet piling, as shown and described.

DESCRIPTION

FIG. 1 is an overall perspective view of my new design; FIG. 2 is a top view thereof; FIG. 3 is a first end view thereof; FIG. 4 is a second end view thereof; FIG. 5 is a front view thereof; FIG. 6 is a rear view thereof; and, FIG. 7 is a top view thereof, the broken lines showing adjacent vinyl sheet pilings are for illustrative purposes only and form no part of the claimed design.

FIG. 1

FIG. 2

FIG. 5

FIG. 3

FIG. 6

FIG. 4

FIG. 7
